UNITED STATES PATENT OFFICE

2,002,087

SHOE HEEL

Jack F. Esterson, Baltimore, Md.

Application July 17, 1931, Serial No. 551,459

2 Claims. (Cl. 36—36)

My invention relates generally to shoe heels and has particular reference to heels which are formed in two portions, detachably secured together by interengaging members on the said 5 portions.

One object of my invention is to provide an improved means whereby the wearing portion of the shoe heel can be quickly and easily detached and replaced by another wearing portion without the use of nails, pegs or similar devices and without the necessity for the services of a shoemaker.

A further object of my invention is to provide a construction which is of simplified character, inexpensive to manufacture and easier to attach or detach than prior constructions.

I have achieved the foregoing objects, and such other objects as may hereinafter appear or be pointed out, in the manner illustratively exemplified in the accompanying drawing, wherein,

Figure 1 is a perspective view showing a shoe heel provided with attachment plates constructed in accordance with one embodiment of my invention.

Figure 2 is a perspective view showing a shoe heel provided with attachment plates constructed in accordance with another embodiment of my invention, and

Figure 3 is a perspective view showing a shoe heel provided with attachment plates constructed in accordance with still another embodiment of my invention.

The heel comprises a portion 1 which is permanently attached to the shoe and a detachable portion or lift 2. Permanently secured to each of these portions is a thin sheet metal attachment plate, these plates being designated in the drawing by the reference numerals 3 and 4.

The plate 3 in accordance with my invention is secured to the permanent heel portion 1 by means of a single screw 5 and the plate 3 is provided with turned down flanges 6 in order to prevent rotation of the plate 3 with respect to the permanent heel portion 1.

The flanges 6 incidentally provide a means for preventing the curling or peeling of the breasting lining 7. The plate 4 may be secured to the detachable heel portion 2 by nails 8 or other suitable fastening means.

In the embodiment of my invention illustrated in Figure 1, the plates conform to the heel and lift both in shape and in size. The plate 3 is provided with two integral flanges 9 bent up from the plate along the curved edge thereof and a

single integral flange 10 bent up from the plate along the forward straight edge thereof. The plate 4 is provided with two recesses 11 cut into the curved edge of the plate, the location and dimensions of these recesses being such that they are adapted to receive with a snug fit the flanges 9 of the plate 3. 5

In order to attach the lift 2 of the heel to the main body portion 1, the plate 4 is engaged with the plate 3 in such manner that the flanges 9 are 10 permitted to enter the recesses 11 with the forward straight edge 12 of the plate 4 resting on the upper edge of the flange 10. A slight pressure is then applied to the parts in a direction to force the plates together, whereupon the flange 10, being resilient, will yield to permit the edge 12 of the plate 4 to snap into position with the adjacent faces of the plates in mutual contact. To facilitate the attachment of the plates, the straight edge 12 of the plate 4 may be slightly 15 beveled. Due to the inherent resiliency of the flanges 9 and 10 the plates are locked together against accidental disconnection. However, should it be desired to remove the lift, all that is necessary is to insert the blade of a knife or a 20 similar instrumentality between the plates to pry them apart. To facilitate this, the plate 4 may be provided with notches 13 along the edge 12.

In the embodiment of my invention illustrated in Figure 2 the plates are considerably smaller 30 than the heel or heel lift and are trapezoidal in form, the side edges of the plates converging towards the rear of the heel. The plate 3 has its side edges 15 slightly turned up and spaced apart 35 a short distance from the permanent heel portion 1. Adjacent to its forward edge and between its side edges the plate 3 is provided with a hump 16.

The plate 4 is seated within a depression 17 formed in the heel lift and has inturned side flanges 18 which provide channels for receiving 40 the side edges 15 of the plate 3. Preferably, the flanges 18 taper from the forward edge of the plate to the rearward edge thereof. The plate 3 also has at its rear edge an inturned flange 19. In the plate 4, at a point between the side edges 45 and at an appropriate distance from the forward straight edge an opening 20 is provided for receiving the hump 16 on the plate 3 in order to prevent the accidental disconnection of the heel lift from the main body portion. 50

To connect the plates, the plate 4 is engaged with the plate 3 in such a manner that the rear portion of the plate 3 is disposed in advance of the forward edge of the plate 4. The plate 3 is now moved rearwardly over the plate 4 and the 55

edges 15 of the plate 3 engage in the channels formed by the flanges 18 until the hump 16 clicks into the opening 20. The flange 19 serves as a stop to prevent further relative movement of the 5 plates.

In the embodiment of my invention illustrated in Figure 3 the plates are generally of the same configuration as the plates of Figure 2 and the size with respect to the heel is in the same proportion as in Figure 2. The plate 3 is provided with an upstanding flange 21 at the forward edge thereof and a similar flange 22 at the rear edge thereof. The plate 4 is seated in a depression 23 formed in the lift and is provided with side flanges 24. In this form of my invention the flanges 21 and 22 of the plate 3 engage the forward and rear edges, respectively, of the plate 4, while the side flanges 24 of the plate 4 engage the corresponding side edges 25 of the plate 3. The depression 23 is extended slightly beyond the rear edge of the plate 4 to leave a narrow space 26 for the reception of the flange 22. To insure a firm gripping engagement between the flanges of each plate and the corresponding edges of the other plate, the flanges are slightly turned in as illustrated in Figure 3.

To attach the plates, one is superimposed upon the other with the rear flange 22 of plate 3 engaged in the narrow space 26 and with the forward edge of plate 4 resting upon the flange 21. A slight pressure is then applied to force the plates together whereupon the flanges 21 and 22 will yield to permit the plate 4 to snap into place.

From the foregoing description it will be evident that I have provided an improved means for detachably connecting a heel lift to the main body portion of a heel, the construction affording security against accidental separation of the parts yet permitting easy and quick separation

when required. It will be observed that in the embodiments of Figures 2 and 3 the plates are concealed when the lift is attached to the main heel portion.

Some changes may be made in the construction and arrangement of the parts of my invention without departing from the real spirit and purpose of my invention and it is my intention to cover by my claims, any modified forms of structure or use of mechanical equivalents, which may be reasonably included within their scope. 5

Having thus described my invention and illustrated its use, what I claim as new and desire to secure by Letters Patent is:—

1. A heel for footwear comprising a main body portion and a detachable portion having a depression therein, a plate permanently secured to each of said portions, said plates occupying relatively small portions of the surface of said portions, one of said plates having side flanges adapted to engage the respective side edges of the other plate, said other plate having end flanges adapted to engage the respective end edges of the said first mentioned plate, the plate on the detachable portion being mounted in said depression and said depression being equal to the combined thicknesses of said plates. 15

2. A heel for footwear comprising a main body portion and a detachable portion, a plate permanently secured to each of said portions and extending within three edges of said portions, one of said plates having side flanges adapted to engage the respective side edges of the other plate, said other plate having end flanges adapted to engage the respective end edges of the said first mentioned plate, the plate secured to the detachable portion being seated in a depression formed in said detachable portion. 30
